UNITED STATES PATENT OFFICE.

ROBERT A. WELCH, OF DOVER, NEW JERSEY.

DESIGN FOR A BOTTLE-RACK.

41,364.

Specification for Design.

Patented May 9, 1911.

Application filed March 1, 1911. Serial No. 611,736. Term of patent 7 years.

To all whom it may concern:

Be it known that I, ROBERT A. WELCH, a citizen of the United States, residing at Dover, in the county of Morris and State of New Jersey, have invented a new, original, and ornamental Design for Bottle-Racks, of which the following is a specification, reference being had to the accompanying drawing, forming part thereof.

The figure is a side view in elevation showing my new design in bottle racks.

I claim:

The ornamental design for a bottle rack, as shown.

ROBERT A. WELCH.

Witnesses:

H. D. MOLLER,
CHAS. J. MOLLER.
